FLUID JET RELAY

Walter L. Benedict, Stoneham, and Sidney J. Finn, Beverly, Mass., assignors to United Shoe Machinery Corporation, Flemington, N. J., a corporation of New Jersey

Application August 25, 1951, Serial No. 243,641

14 Claims. (Cl. 137—83)

1

This invention relates to fluid jet relays and has for its principal object the provision of a novel and improved fluid jet relay which is highly efficient, extremely sensitive and very dependable in operation.

Fluid jet relays, as hitherto constructed, usually include a jet pipe, formed with a discharge nozzle, and a receiver member, provided with two openings for receiving fluid under pressure delivered thereto from the jet nozzle, these parts being associated with a housing, on which the jet pipe is pivotally mounted, with suitable connections for admitting fluid under pressure to the jet pipe and for conducting the pressure fluid received by the openings in the receiver member to the opposite ends of a reversible fluid pressure motor such, for example, as a piston cylinder. These devices are also provided with means for displacing the jet nozzle, relatively to the two openings, thereby to effect an unbalancing of the pressure of the fluid delivered to the motor so as to cause it to operate in one direction or the other at a rate proportional to the extent of displacement of the jet nozzle. Fluid jet relays of this type are well known and are frequently used as component parts of servo mechanisms in which there are included so-called feed-back connections for restoring the jet nozzle to a centered position, relatively to the receiver openings, in response to operation of the fluid motor.

While fluid jet relays of the type just described are used quite widely for various purposes, they are not entirely satisfactory under all conditions, particularly where a high efficiency and extreme sensitivity must be coupled with dependability of operation. For example, in order to compensate for the unequal thermal expansion of the various parts when the operating fluid, such as oil, becomes heated during the operation of the jet relay, it has been necessary to provide a substantial operating clearance, between the jet nozzle and the receiver member, which materially decreases the efficiency of the device. Also, because of static friction in the bearings of which the jet nozzle is pivotally mounted, a certain stickiness of action may result which not only requires the application of a considerable force initially to displace the nozzle and thereby greatly decreases the sensitivity and response of the relay, but also renders the relay somewhat undependable in operation.

With the view of overcoming these difficulties, the herein illustrated jet relay, in accordance with a feature of this invention, provides an arrangement for automatically compensating for

2

the thermal expansion of the several parts so that an extremely close operating clearance may be maintained between the jet nozzle and the receiver member, thereby substantially increasing the efficiency of the relay. More particularly, the jet nozzle of the relay is carried by a pipe which is mounted on a header block and this header block, in turn, is supported on a base member by means of a pair of conduits which extend upwardly from the base member. Surrounding the base member, on which the receiver block is supported, and extending upwardly therefrom, is a housing, and the header block is slidably fitted in the upper end of this housing. The two conduits which support the header block and the pipe which carries the jet nozzle are constructed of materials having substantially the same linear coefficient of expansion so that, as the temperature of the operating fluid increases, these parts expand by the same amount and the operating clearance between the jet nozzle and the receiver block will remain the same. Accordingly, the operating clearance between the jet nozzle and the receiver block can be reduced to an absolute minimum which will be unchanged by temperature variations during the operation of the relay. Because of the extremely small operating clearance which is thus provided, the efficiency of the jet relay is very greatly increased.

30 In accordance with another feature of the invention, the flexibility of the pipe which carries the jet nozzle is utilized to permit displacement of the nozzle relatively to the openings in the receiver block thereby eliminating the disadvantages resulting from the use of frictional bearings. Thus, the pipe which supports the nozzle and is adjustably mounted at its upper end in the header block, comprises a metallic tube of considerable length. The jet nozzle is secured directly to the lower end of this tube with its discharge orifice directly over and closely adjacent to the receiver block. With this arrangement, displacement of the jet nozzle, relatively to the openings in the receiver block, may be effected by 40 slightly bending the flexible jet pipe without any stickiness or frictional resistance such as would be present if the jet pipe were supported in bearings.

50 Preferably, and as herein illustrated, spring means are provided for accurately centering the jet nozzle, relatively to the openings in the receiver block. This spring means operates directly on the jet nozzle which, due to the considerable length and flexibility of the jet pipe, acts more or less like a free body and responds most readily

to forces tending to displace it against the resistance of the spring means. In addition the spring means is arranged to function as a parallel motion linkage and thus to prevent undesirable lateral and/or rotational movements of the jet nozzle, relatively to the openings in the receiver, in response to forces applied thereto during the operation of the jet relay.

These and other objects and features of the invention will appear in the following detailed description of the embodiment thereof illustrated in the accompanying drawings and will be pointed out in the claims.

In the drawings,

Fig. 1 is a view in elevation of a jet relay embodying the features of this invention, with certain parts broken away and others shown in section;

Fig. 2 is a view in elevation of the lower portion of the jet relay, with certain parts shown in section substantially on line II—II of Fig. 1 and looking in the direction of the arrows;

Fig. 3 is a plan view of the lower portion of the jet relay, with certain parts shown in section, substantially on line III—III in Fig. 1 and looking in the direction of the arrows;

Fig. 4 is a plan view of a lower portion of the jet relay shown at an enlarged scale and with certain parts in section substantially on lines IV—IV of Fig. 2 and looking in the direction of the arrows;

Fig. 5 is a sectional view of a portion of the lower part of the jet relay substantially on line V—V of Fig. 4 looking in the direction of the arrows; and

Fig. 6 is a schematic plan view of certain parts of the jet relay at a greatly enlarged scale.

Referring to these drawings, and particularly to Fig. 1 thereof, the jet relay therein illustrated comprises a cylindrical housing 10, a base member 12 on which there is supported a receiver block 14, a header block 16 which is supported on the base member by means of a pair of conduits 18, 18, and a jet pipe 20 provided with a jet nozzle 22. The base member 12 is secured to the lower end of the housing 10 by means of screws 24, 24 which pass through a flange 26 on the base member and are threaded into the housing. At its upper end, the housing is closed by a cover plate 28, secured to the housing by screws 30, 30 and provided with a central bore 32. At their opposite ends, the conduits 18, 18 are force-fitted and sweated into bores 34, 34 and 36, 36, formed respectively in the base member 12 and in the header block 16, while the header block is slidably fitted in the central bore 32 of the cover plate 28 which forms the upper end of the housing. The upper end of the jet pipe 20 is similarly secured in a bore 38 formed in a cylindrical member 40 which is fitted in a bore 42 in the header block. The member 40 has a radially extending flange 44 and is secured to the header block by means of screws 46, 46, passing through this flange. It is important that the conduits 18, 18 be positively locked to the base member 12 and header block 16 and that the pipe 20 be fixed to the member 40 with equal security. For this purpose the force fitting and sweating together of these parts may be supplemented by pins, not shown.

The bores 34, 34, in the base member, are connected to an inlet pipe 50 by means of a pair of angularly disposed intersecting bores 52, 52, which are plugged at their outer ends, and a radial bore 54, Fig. 4. The inlet pipe extends

through the housing 10 and is secured thereto by means of a flange 56 and screws 58, 58, Fig. 3. The bores 36, 36, in the header block 16, are connected, by radial ports 60, 60, to an annular groove 62, formed in the cylindrical member 40, and this groove, in turn, is connected to the bore 38 and the jet pipe 20, by means of radial ports 64, 64. Leakage of the pressure fluid between the cylindrical member 40 and the bore 42 in the header block is prevented by suitable packing rings 66, 66 fitted in grooves in the cylindrical member, above and below the groove 62, Fig. 1. A discharge pipe 68 is connected to the interior of the housing through a bore 69 in the base member 12.

The receiver block 14 is made up of two parts 70, 72 which are fitted in a diametrically disposed groove 74, formed in the upper side of the base member 12, and these parts are held in place in this groove by means of clamps 76, 76 and screws 78, 78, Figs. 2 and 4. The receiver block 14 is provided with two openings 80, 82 formed, respectively, in the parts 70, 72. As will be seen in Fig. 4, these openings are disposed symmetrically on the opposite sides of a vertical plane x—x which coincides with the meeting plane of the two receiver block parts 70, 72 and are formed by rectangular slots cut vertically through each of these parts, see also Fig. 5. On their lower sides, the receiver block parts 70, 72 are each cut away at 84, 86 to connect the openings 80, 82, respectively, with angularly disposed passageways 88, 90 in the base member. These passageways, in turn, open into vertically disposed bores 92, 94 in the base member, Figs. 4 and 5, and connected to these bores are discharge pipes 96, 98, Figs. 1 and 2.

At its lower end, the jet pipe 20 is flattened out to the shape indicated in broken lines in Fig. 6 to form the jet nozzle 22 and its cylindrical bore is swaged to form an elongated rectangularly shaped orifice 100, also indicated by broken lines in Fig. 6. Just above the nozzle 22, a rectangularly shaped block 102 is fitted over and sweated to the jet pipe 20. Embracing this block and secured thereto by a screw 104 is a U-shaped yoke 106 having a pair of vertically extending sides 108, 110. Mounted on the base member 12, by means of a screw 111, is a bracket member 112 having a pair of upwardly extending arms 114, 116. Carried by these arms are a pair of leaf springs 118, 120 which extend on the opposite sides of, and are secured to the sides 108, 110 of the yoke 106. Fastened to the housing 10, by means of a flange 122 and screws 124, is a gland 126 in which there is mounted a plunger 128 which extends into the housing and is there connected to the side 108 of the yoke 106 by a flexible metal strip 130 and a connecting block 132. Secured to the outer end of this plunger is a second flexible metal strip 134.

In use, the inlet pipe 50 of the jet relay is connected to a suitable source of fluid under pressure while the discharge pipes 96, 98 are connected to the opposite ends of the fluid-pressure-operated motor the action of which is to be controlled by the relay, and the overflow pipe 68 is connected to a sump. Also, the plunger 128 is connected, by means of the flexible metal strip 134, to a suitable operating mechanism such, for example, as one of the three operating mechanisms of the machine disclosed in United States Letters Patent No. 2,644,968, granted July 14, 1953 upon application of Walter L. Benedict, Harry D. Goodnow and Frank Pulsifer. As is explained in

that patent, each of these three operating mechanisms is actuated by a work-engaging feeler and the jet relay controls the flow of pressure fluid to a fluid-pressure-operated motor in such a way as to maintain the work in a desired position as determined by the feeler. In such an arrangement, the jet relay functions as the controlling device of a closed loop servo mechanism in which the feed connections include the work and the work-engaging feeler. It will be understood, however, that the arrangement outlined above is suggested merely for purposes of illustration and that the jet relay of this invention is capable of use in other types of apparatus wherein the operation of a fluid-pressure-operated motor is to be efficiently and dependably controlled in an extremely sensitive manner.

The jet pipe 20 is of such a length that the nozzle 22, at its lower end, may be readily displaced by flexing of the pipe. The arms 114, 116 of the bracket 112 and the leaf springs 118, 120, which are connected at their opposite ends to the aforementioned arms and also to the yoke member 106 which is associated with the nozzle, are so disposed as to urge the nozzle to a centered position, i. e., a position in which the elongated orifice 100 of the nozzle 22 is symmetrically located with respect to the vertical plane $x-x$ which passes through the inner edges of the receiver block openings 30, 32. These springs also function as a pair of parallel links so that, when the nozzle is displaced in either direction from its centered position, by a force applied thereto through the plunger 128, it will be constrained to move in a direction substantially perpendicular to the plane $x-x$ and the orifice will remain at all times substantially parallel to this plane, as well as substantially centered, in a lengthwise direction relatively to the opposite ends of the openings 30, 32 in the receiver block.

The openings 30, 32 are of rectangular shape, see Fig. 6, and are spaced apart between their adjacent ends by a distance approximately equal to their width. For the purpose of obtaining a sensitive control, these openings are quite narrow in width, while the width of the orifice 100 in the nozzle 22 is, as can be seen in Fig. 6, approximately one-third of the width of these openings. Preferably, and in the herein illustrated construction, the wall thickness of the jet pipe 20 is such that, when the nozzle is in its centered position, as shown in Fig. 6, there is a small gap left between each side of the nozzle and the outer edge of one or the other of the openings 30, 32. The operating clearance between the lower end of the nozzle 22 and the upper surface of the receiver block 14 is, in a manner which will be explained below, maintained at an absolute minimum value. Although the dimensions of the several parts, i. e., nozzle 22, openings 30, 32, orifice 100, and the clearance between the nozzle and the receiver blocks may, of course, be varied to accommodate different operating conditions, the dimensions of a jet relay of this type, which has proved to be very satisfactory in operation, are given below by way of an example: width of openings 30, 32 (dimension a in Fig. 6) = .030 inch; length of openings approximately .125 inch; width of orifice 100 (dimension b in Fig. 6) = .010 inch; length of orifice sufficient to overlap the opposite ends of the openings, as shown in Fig. 6; wall thickness of nozzle 22 (dimension d in Fig. 6) = .023 inch; width of gaps at the opposite sides of the nozzle when the nozzle is in centered position (dimension g in Fig. 6) = .002 inch, and

an operating clearance between the lower end of the nozzle and the upper side of the receiver plate (dimension e in Fig. 5) in the magnitude of .0001 inch. With a jet relay having the dimensions outlined above, an efficiency, i. e., ratio of the maximum outlet pressure to the inlet pressure, of approximately 94%, was obtained with a capacity of approximately one and one-third gallons per minute at 750 lb./sq. in. inlet pressure.

The minimum operating clearance between the lower end of the nozzle 22 and the upper surface of the receiver block 14 is provided in the following manner. The base member 12, receiver block 14, conduits 18, 19, and header block 16, and the jet pipe 20 and cylindrical member 40, are first accurately assembled in such a way that the distance from the upper end of the header block 16 to the upper surface of the receiver block 14 is a few thousandths of an inch less than the distance from the lower surface of the flange 44 on the cylindrical member 40 to the lower end of the jet nozzle 22. Next, the jet nozzle, jet pipe, and the cylindrical member 40, which have first been accurately assembled, as above noted, are inserted down through the bore 42 in the header block 16 and the cylindrical member 40 is fitted into the bore 42 until the flange 44 rests upon a thin metallic shim 300, previously placed on the upper surface of the header block. This shim is selected from a number of standard shims, varying in thickness by one-thousandth of an inch, so that, when the member 40 is secured to the header block 16, by means of the screws 46, 48 which pass through the flange 44 and also through the shim 300, the distance from the lower side of this flange to the lower end of the nozzle 22 will exceed the distance from this flange to the upper surface of the receiver block by an amount which is somewhat less than one-thousandth of an inch. Accordingly, the lower end of the nozzle will be forced against the upper surface of the receiver block when the screws 46, 48 are tightened. Now, after the yoke 106 has been secured to the block 102, a small amount of lapping compound is placed on the receiver block and, by manipulation of the nozzle, its lower surface is lapped away until there is an operating clearance between the lower end of the nozzle and the upper surface of the receiver block sufficient to permit unrestricted movement of the nozzle relatively thereto. The foregoing procedure will result in the provision of a clearance space of such small magnitude that it can hardly be measured, but which is believed to be considerably less than .0001 inch. Also, the upper surface of the receiver block 14 will be lapped to a very slightly cupped surface, in the vicinity of the lower end of the nozzle 22, and the radius of curvature of this surface will be substantially the same as the radius of curvature of the path of movement of the lower end of the nozzle. After the nozzle has thus been lapped in, the base member, carrying the conduits 18, the header block 16, the cylindrical member 40 and the jet pipe 20, are inserted in the lower end of the housing 10 and secured thereto, and the cover plate is fitted over the header block 16 and secured in place on the upper end of the housing.

The extremely high operating efficiency of the herein illustrated jet relay is due primarily to the minimum operating clearance between the nozzle 22 and the receiver block 14, while the use of such a small operating clearance is made possible by the manner in which the jet relay is constructed. As is indicated by the arrows in Fig. 1, the pres-

sure fluid from the source, not shown, is conducted upwardly to the header block 16, from the base member 12, through the conduits 18, 18, and thence downwardly to the nozzle 22 through the jet pipe 20. The conduits 18, 18 and jet pipe 20 are constructed of materials having the same linear coefficient of thermal expansion and are of substantially the same length and of similar cross-sectional shape and area. Also, the header block 16, which is supported on the upper ends 10 of these conduits and to which the jet pipe is secured, is slidably fitted in the bore 32 formed in the cover plate 28 of the housing 10. Accordingly, when the temperature of the operating fluid increases or decreases, during the operation of the jet relay, the linear expansion of the conduits 18, 18, permitted as the header block 16 slides in the bore 32, is exactly offset by the linear expansion of the jet pipe 20. Hence, under all operating conditions and with the full range of operating temperatures, the clearance between the nozzle and the receiver block will remain constant. Also, because of the cupped surface on the receiver block, formed during the "lapping-in" of the nozzle, this clearance will be maintained during displacement of the nozzle from its centered position.

The herein illustrated jet relay also affords extreme sensitivity of control and dependable operation. Referring to Fig. 6, it will be observed, when the jet is in its centered position, that the pressure of the fluid in the two discharge pipes 96, 98 will be equalized and will be of a magnitude which depends on the pressure of the fluid admitted to the nozzle through the inlet pipe 50 and the relation between the volume of fluid delivered to the two openings 80, 82 and the amount exhausted through the gaps between the opposite sides of the nozzle and the outer edges of these openings and between the nozzle and the upper surface of the receiver block. Thus, the fluid-pressure-operated motor which is connected to these discharge pipes, e. g., a piston in a cylinder, will be held stationary by fluid under equal pressure applied to its opposite ends. This balance will, however, be disturbed, and movement of the motor in one direction or the other effected by the slightest displacement of the nozzle 22 from its centered position, as by a force applied thereto by the plunger 123. For example, if the nozzle 22 is displaced, upwardly in Fig. 6 (to the right in Figs. 1 and 4), by an amount of .005 inch, the orifice 100 will entirely overlap the opening 80, the gap between the upper side of the nozzle and the outer edge of the opening 80 will be closed and the gap between the lower side of the nozzle and the outer edge of the opening 82 will be increased to .007 inch. Accordingly, the pressure of the fluid in the discharge pipe 96 will considerably exceed the pressure of the fluid in the discharge pipe 98 with the result that the fluid-pressure-operated motor, controlled by the jet relay, will be caused to operate in one direction at a rate proportional to the difference between the pressures of the fluid in these two pipes. Further displacement of the jet nozzle will, of course, increase the unbalancing of the pressures of the fluid in these pipes and correspondingly increase the rate of movement of the fluid-pressure-operated motor up to a point (approximate displacement of the nozzle from centered position of .007 inch) where the difference of the pressure of the fluid in the two discharge pipes 96, 98 is at a maximum. In this connection, it may be pointed out that, with a

relay of the dimensions set forth above, by way of example, further movement of the nozzle beyond the .007 inch displacement point, results in only a very slight increase in this pressure difference and, for practical purposes, the maximum nozzle displacement is .007 inch. Thus, by a very slight displacement of the nozzle 22 the operation of a fluid-pressure-operated motor may be directly and sensitively controlled.

Inasmuch as the displacement of the nozzle 22 is effected, against the slight resistance of the leaf springs 118, 120, by flexing of the jet pipe 20, the forces required to displace the nozzle are relatively small. Moreover, inasmuch as no bearings of any kind are used, all stickiness which might result from friction in the bearings, is avoided and the forces required to move the nozzle remain uniform and proportional to the amount of nozzle displacement. Thus, the relation is most dependable and consistent in operation:

Having thus described our invention, what we claim as new and desire to secure by Letters Patent of the United States is:

1. A jet relay comprising a housing, a base member, a jet receiver including a pair of openings associated with said base member, a pair of conduits mounted on the base member and extending upwardly within said housing, a header block supported on said conduits, a flexible pipe secured to the header block and extending downwardly within said housing, said header block being provided with passageways for connecting said conduits to said flexible pipe, a jet nozzle carried on the lower end of said flexible pipe and provided with a discharge orifice positioned directly over and closely adjacent to said jet receiver, and means extending through the housing for displacing said nozzle, relatively to the openings in said jet receiver, by bending the flexible pipe.

2. A jet relay comprising a housing, a base member associated with said housing, a jet receiver block provided with a pair of openings and supported on said base member, a pair of conduits mounted on the base member and extending upwardly within said housing, a header block supported on the said conduits, a flexible pipe secured to the header block and extending downwardly within the housing, said header block being provided with passageways for connecting said conduits to said flexible pipe, a jet nozzle carried on the lower end of said flexible pipe and provided with a discharge orifice positioned directly over and closely adjacent to said receiver block, and means extending through said housing for displacing said nozzle, relatively to the openings in the receiver block, by bending the flexible pipe.

3. A jet relay comprising a housing, a base member, a jet receiver including a pair of openings associated with said base member, a pair of conduits mounted on the base member and extending upwardly within said housing, a header block supported on the upper ends of said conduits and slidably fitted in the housing, a flexible pipe secured to the header block and extending downwardly within the housing, said header block being provided with passageways for connecting said conduits to said flexible pipe, a jet nozzle carried on the lower end of said flexible pipe and provided with a discharge orifice positioned directly over and closely adjacent to said jet receiver, and means extending through said housing for displacing said nozzle, relatively to said

openings, said pair of conduits and said flexible pipe being constructed of materials having substantially the same linear coefficient of expansion.

4. A jet relay comprising a housing, a base member associated with said housing, a receiver block supported on the base member, a pair of conduits mounted on the base member and extending upwardly within said housing, a header block supported on the upper ends of said conduits and slidably fitted in the housing, a flexible pipe secured to the header block and extending downwardly within the housing, said header block being provided with passageways for connecting said conduits to said flexible pipe, a jet nozzle carried on the lower end of said flexible pipe and provided with a discharge orifice positioned directly over and closely adjacent to said receiver block, and means extending through said housing for displacing said jet nozzle relatively to said openings, said pair of conduits and said flexible pipe being constructed of materials having substantially the same linear coefficient of expansion.

5. A jet relay comprising a housing, a base member, a jet receiver including a pair of openings associated with said base member, a pair of conduits mounted on the base member and extending upwardly within said housing, a header block supported on the upper ends of said conduits and slidably fitted in the housing, a pipe mounted on the header block and extending downwardly within the housing, said header block being provided with passageways for connecting said conduits to said pipe, a jet nozzle carried on the lower end of said pipe and provided with a discharge orifice positioned directly over and closely adjacent to said jet receiver, and means extending through said housing for displacing said nozzle, relatively to the openings in said jet receiver, said pair of conduits and said pipe being constructed of materials having substantially the same linear coefficient of expansion.

6. A jet relay comprising a housing, a base member, a receiver block provided with two openings and supported on said base member, a pair of conduits mounted on the base member and extending upwardly within said housing, a header block supported on the upper ends of said conduits and slidably fitted in the housing, a pipe mounted on the header block and extending downwardly within the housing, said header block being provided with passageways for connecting said conduits to said pipe, a jet nozzle carried on the lower end of said pipe and provided with a discharge orifice positioned directly over and closely adjacent to said jet receiver, and means extending through said housing for displacing said nozzle, relatively to the openings in said jet receiver, said pair of conduits and said pipe being constructed of materials having substantially the same linear coefficient of expansion.

7. A jet relay comprising a housing, a base member, a jet receiver associated with said base member, a pair of conduits mounted on the base member and extending upwardly within said housing, a header block supported on the upper ends of said conduits, a flexible pipe secured to the header block and extending downwardly within the housing, a jet nozzle secured to the lower end of said flexible pipe and provided with a discharge orifice positioned directly over and closely adjacent to said jet receiver, a pair of openings in the jet receiver disposed on the op-

posite sides of a plane substantially parallel to the longitudinal axis of said flexible pipe, spring means associated with said base member and said jet nozzle arranged yieldingly to hold the nozzle in a position in which its discharge orifice is centered with respect to said openings, and means extending through the housing and connected to the nozzle for displacing said nozzle, relatively to said openings, in directions normal to the aforementioned plane and against the resistance of said spring means.

8. A jet relay comprising a housing, a base member associated with said housing, a receiver block supported on the base member, a pair of conduits mounted on a base member and extending upwardly within said housing, a header block supported on the upper ends of said conduits, a pipe secured to the header block and extending downwardly within the housing, a jet nozzle secured to the lower end of said pipe and provided with a discharge orifice positioned directly over and closely adjacent to said receiver block, a pair of openings in the receiver block on the opposite sides of a plane substantially parallel to the longitudinal axis of said pipe, spring means associated with said base member and said nozzle arranged yieldingly to hold the nozzle in a position in which its discharge orifice is centered with respect to said opening, and means extending through the housing and connected to the nozzle for displacing said nozzle, relatively to said openings, in directions normal to the aforementioned plane and against the resistance of said spring means.

9. A jet relay comprising a housing, a base member associated with said housing, a receiver block supported on the base member, a pair of conduits mounted on the base member and extending upwardly within said housing, a header block supported on the upper ends of said conduits and slidably fitted in the housing, a flexible pipe secured to the header block and extending downwardly within the housing, a jet nozzle secured to the lower end of said flexible pipe and provided with a discharge orifice positioned directly over and closely adjacent to said receiver block, a pair of openings in the receiver block disposed on the opposite sides of a plane substantially parallel to the longitudinal axis of said flexible pipe, spring means associated with said base member and said jet nozzle arranged yieldingly to hold the nozzle in a position in which its discharge orifice is centered with respect to said openings, and means extending through the housing and connected to the nozzle for displacing said nozzle, relatively to said openings, in directions normal to the aforementioned plane and against the resistance of said spring means.

10. A jet relay comprising a housing, a base member, a jet receiver associated with said base member, a pair of conduits mounted on the base member and extending upwardly within said housing, a header block supported on the upper ends of said conduits and slidably fitted in the housing, a pipe mounted on the header block and extending downwardly within the housing, a jet nozzle secured to the lower end of said pipe and provided with a discharge orifice positioned directly over and closely adjacent to said jet receiver, a pair of openings in the jet receiver disposed symmetrically on the opposite sides of a plane substantially parallel to the longitudinal axis of said pipe, spring means associated with said base member and said jet nozzle arranged yieldingly to hold the nozzle in a position in which

11

its discharge orifice is centered with respect to said openings, and means extending through the housing and connected to the nozzle for displacing said nozzle, relatively to said openings, in directions normal to the aforementioned plane and against the resistance of said spring means.

11. A jet relay comprising a housing, a base member, a jet receiver associated with said base member and provided with a pair of openings, symmetrically disposed on the opposite sides of a plane, a header block, a flexible pipe mounted on the header block and extending downwardly within the housing, a jet nozzle secured to the lower end of said pipe and provided with a discharge orifice, said orifice being of elongated shape and of a length to overlap said openings at their opposite ends, and means extending through the housing and connected to said nozzle for displacing the nozzle, relatively to said openings, by bending the flexible pipe, and means associated with said base member and said nozzle for constraining it to move in a path perpendicular to said plane.

12. A jet relay comprising a housing, a base member, a jet receiver associated with said base member and provided with a pair of openings, symmetrically disposed on the opposite sides of a plane, a pair of conduits mounted on the base member and extending upwardly within the housing, a header block supported on said conduits and slidably fitted in the housing, a flexible pipe mounted on the header block and extending downwardly within the housing, a jet nozzle secured to the lower end of said pipe and provided with a discharge orifice, said discharge orifice being of elongated shape and of a length to overlap said openings at their opposite ends, means extending through the housing and connected to said nozzle for displacing the nozzle, relatively to said openings, by bending the flexible pipe, and means associated with said base member and said nozzle for constraining it to move in a direction perpendicular to said plane.

13. A jet relay comprising a housing, a base member, a jet receiver associated with said base member and provided with a pair of openings,

12

symmetrically disposed on the opposite sides of a plane, a header block, a flexible pipe mounted on the header block and extending downwardly within the housing, a jet nozzle secured to the lower end of said pipe and provided with a discharge orifice, said discharge orifice being of elongated shape and of a length to overlap said openings at their opposite ends, and means extending through the housing and connected to said nozzle for displacing the nozzle, relatively to said openings, by bending the flexible pipe, and spring means associated with said base member and said nozzle for constraining it to move in a direction perpendicular to said plane.

14. A jet relay comprising a housing, a base member, a jet receiver associated with said base member and provided with a pair of openings, symmetrically disposed on the opposite sides of a plane, a pair of conduits mounted on the base member and extending upwardly within the housing, a header block supported on said conduits and slidably fitted in the housing, a flexible pipe mounted on the header block and extending downwardly within the housing, a jet nozzle secured to the lower end of said pipe and provided with a discharge orifice, said discharge orifice being of elongated shape and of a length to overlap said openings at their opposite ends, means extending through the housing and connected to said nozzle for displacing the nozzle, relatively to said openings, by bending the flexible pipe, and spring means associated with said base member and said nozzle for constraining it to move in a direction perpendicular to said plane.
